SLUR CAM PARTICULARLY ADAPTED FOR
USE IN STRAIGHT KNITTING MACHINES
EMPLOYING HORIZONTALLY RECIPRO-
CATABLE SINKERSGeorge F. Kettleband, Providence, R. I., assignor
of one-half to John W. Staton, West Barrington, R. I., and J. William Staton, Cranston, R. I.

Application November 16, 1934, Serial No. 753,364

13 Claims. (Cl. 66—110)

My invention relates to improvements in slur cams particularly adapted for use on straight hosiery knitting machines having horizontally reciprocatable sinkers.

5 An object of my invention is to provide a slur cam structure which will yield to prevent breakage of any contacting or operating parts should an obstruction of any kind fall between the sinkers, jacks and verge plate and thus being flexible 10 should the sinkers and jacks for any reason fail, to prevent the verge plate from damage and breakage.

A further feature of my invention is to provide 15 a yielding device which will prevent stoppage of the slur bar due to any slur cam obstruction, thereby tending to take the strain off from the Coulier motion and prevent breakage or damage of the same.

Great difficulty has been experienced in knitting 20 machines of this description with sinker breakage and a further feature of my invention is to provide a yieldable slur cam which while forcing the sinkers against the verge plate against the pressure of the spring will absorb any shock 25 and thereby tend to prevent sinker breakage at the common two points thereof, namely, at the rivets of reinforcement of the sinkers and prevent crystallization between the noses and fingers thereof and breakage at these points.

30 A further feature of my invention is that the slur cam may be readily adjusted to force the sinker backs closer to the verge plate than hitherto for more accurate adjustment thereof without fear of damage to the same and thereby lay a more even course of stitches and thus provide a more evenly knitted fabric.

A further feature of my invention is to provide 35 a yieldable slur cam which due to its flexibility and ability to give way to obstructions will tend to save wear on the slur cam itself and thus obviate the necessity for changes in the original setting of the slur cam as it wears down in use.

A further feature of my invention is to provide 40 a structure which if the slur cam is set to bring the sinker backs too close to the verge plate will yield to prevent wear and breakage on all parts which come in contact with it either directly or indirectly.

45 Further features of my invention are to provide a novel type of slur cam, which may be constructed in a simple fashion of a simple number of parts, which is inherently strong and in which the spring means thereof is carefully concealed 50 within the housing for the slur cam slide to pre-

vent dust, dirt, oil, etc. from getting in contact therewith and interfering with its action.

A further feature of my invention is to provide a transverse adjustment for the slur cam which of itself will temporarily yield when the slur cam 5 indirectly abuts the obstruction and which will immediately return to its original setting when the obstruction is passed.

A further object of my invention is to provide a finer knitted fabric by permitting a closer setting of the sinker backs relative to the verge plate by eliminating the danger of breakage formerly existing when the slur cam to advance the sinkers was set too close to the verge plate.

A further feature of my invention is to automatically compensate without danger of breakage 15 from any variation from a true linear edge in the verge plate.

These and such other objects of my invention as may hereinafter appear will be best understood 20 from a description of an embodiment thereof, such as is shown in the accompanying drawings.

In the drawings, Fig. 1 is a perspective view of 25 the rear end of a portion of a straight knitting machine having horizontally reciprocatable sinkers showing the slur cam reciprocatably mounted on the slur cam bar with the front surface thereof abutting the rear surface of the jacks to move 30 the sinkers back and forth against the verge plate on the sinker bed.

Fig. 2 is a transverse sectional view of the parts 35 of the knitting machine shown in Fig. 1 taken along the line 2—2 of Fig. 1.

Fig. 3 is a plan view of the parts of the knitting machine shown in Fig. 1 with an obstruction such as a screw fallen in between the rear edge of the verge plate and the front edge of the sinker backs showing how my improved slur cam yields to prevent 40 breakage or wear on any adjacent part on such an occurrence.

Fig. 4 is a transverse sectional view taken through my improved type of slur cam along the line 4—4 of Fig. 3.

In the drawings, wherein like characters of reference indicate like parts throughout, 10 generally indicates an improved type of slur cam constructed in accordance with my invention.

In order that the functioning of my improved 50 device may be best understood I have shown in the drawings certain adjacent parts of a straight knitting machine and I have shown a section thereof. As shown in Fig. 1 I have shown the head rail 12 extending substantially the length of 55

the machine and a sinker bed 14 suitably mounted on said head rail. The sinker head or bed has an upper portion 16 projecting over the lower portion 18 thereof and said portions 16 and 18 are provided with adjacently oppositely aligned transverse grooves 20 and 22 respectively to guide the sinkers 24 in their horizontally reciprocatable courses. The sinkers 24 include the reinforced backs 26 which project upwardly at right angles from the rear ends thereof and the usual suitably shaped noses 28. The upper surface of the upper portion 16 of the sinker bed is inclined rearwardly as shown and has mounted thereon the verge plate 30 terminating in a rear edge 32 adjustably set at different distances relative to the rear end of the upper portion 16 of the sinker head. The jacks 34 are suitably mounted on the jack bed or bar 36 extending longitudinally of the section. The jacks are provided at the lower ends 38 with the inclined slots 40 for mounting on said jack bed 36 and normally project vertically pivotally upwardly therefrom and have at their upper ends the enlarged front portions 42 adapted to abut the rear ends of the sinker backs 26 to urge the sinkers forward until the front edges of the sinker backs 26 abut the rear edge 32 of the verge plate 30, the sinkers being moved backwards in use as usual by the usual catch bar motion (not shown.) The usual slur cams 10 are reciprocatably mounted on the guide bar 44 which extends the length of the machine and are reciprocated back and forth in the rear of their respective sinker sections by the slur cam bar 46 on which they are mounted, a slur cam 10 being provided for each section. The slur cam is adapted to abut the rear surfaces 48 of the jacks as usual and pivot them forwards to move the sinkers forwardly.

One feature of my improved construction of slur cam is that I provide yielding spring means abutting the slur cam to permit yielding of the slur cam if the verge plate or bar should be set too close, or an obstruction should come between the sinker back and the verge plate, or for any other reason, said spring means being normally completely concealed within the slur cam housing 50 and another desirable feature is to provide a guideway which will permit movement of the slide in a single line to obviate any tilting movement whatsoever thereof.

While my improved slur cam is particularly adapted for use in the type of machine described, as far as the inherent features of my construction are concerned it may be adapted for use in any desired type of a knitting machine.

The slur cam 10, in my preferred embodiment, includes a plate 52 provided with the longitudinal channel 54 on the lower surface thereof for sliding on said slur cam guide bar 44 and means, such as the bolts 56 projecting downwardly through suitable holes in said plate 52 and suitable aligned holes in said slur cam bar 46 to secure said plate 52 to said slur cam bar 46 to cause reciprocation of said plate. I provide the transversely extending ribs 58 having the flat inner surfaces 60 near the front and rear thereof to provide a guideway extending transversely over said plate.

I provide a transversely movable slide 62 mounted in said guideway and adapted to have the side walls 64 continuously abut the front and rear portions 60 of said ribs and having a front end 66 projecting forwardly beyond the front edge of said plate 52. The front edge of said slide

may be provided with suitable slur cam surfaces, which as usual include the flat central cam surface 68 and the cam surfaces 70 tapering rearwardly from the ends of said flat cam surface 68, in the preferred embodiment shown, to the rounded ends 72. In my preferred embodiment, however, I provide a separate slur cam plate 74 having said slur cam plate surfaces 68 and 70 and rounded ends 72 formed thereon adapted to have the rear end 76 thereof secured underneath the 10 front projecting end 66 of said slide 62, such as by the bolts 78 projecting upwardly through suitable holes in the rear end of said slur cam 74 and front end of said slide 62 as shown in Fig. 4. 15

The slide 62 is suitably retained between said ribs 58 in the guideway formed by said ribs and against the upper surface of said plate 52 by the plate 80 adapted to extend over said guideway and having suitable holes in the outwardly projecting sides thereof to receive the screws 82 to 20 clamp said plate 80 to said ribs 58 to form the upper wall of the housing 50 for housing the slur cam slide within. 25

I provide spring means mounted in said housing 50, normally urging said slide 62 forward yieldable to permit rearward movement thereof. In my preferred embodiment said spring means is preferably constructed and mounted as follows: The rear portion of the guideway formed between said ribs 58 has projecting upwardly therefrom suitable stop means 84 substantially centrally thereof, in my preferred embodiment comprising the bolt 84 screwed within a suitable hole in the upper surface of said plate 52 and I provide spring means, such as the helical spring 86 having the rear end thereof adapted to abut said stop means 84, and the front end thereof adapted to abut the rear surface of the front end 88 of a transverse slot 87 formed centrally in said slide 62. It is thus obvious that if the slur cam should strike any obstruction or abutment tending to cause rearward motion of said slur cam 74 or slide 62 that the spring 86 will become compressed within said slot 87 to permit said rearward movement of said slide 62 and attached slur cam 74. 45

I also provide means to adjust the normal transverse position of said slide and permit said rearward movement thereof and in my preferred embodiment said means includes the lug 92 projecting rearwardly from the rear end of said plate 52 slightly spaced from the center thereof. I provide the screw 94 mounted substantially centrally of the rear end 96 of said slide 62 and I provide the circular nut 98 having the teeth 100 on the periphery thereof and threadedly adjustably mounted on said rearwardly projecting screw means 94 so as to have the front surface 102 thereof abut said plate lug 92 projecting rearwardly from said plate 52. It is obvious therefore that with said lug 92 continuously abutting the front surface 102 of said rotating circular nut 98 that rotation of said nut in one direction will cause forward movement of said slide 62 and in the opposite direction rearward movement of said slide. I also provide means to lock said nut 98 in adjustable positions permitting rearward motion of said slide and in my preferred embodiment said means includes the combination of said teeth 100 extending across said circular nut and a flat spring member 104 having the lower end 106 thereof mounted on one edge of said plate 52 extending upwardly over said nut 98 and terminating in an end bent downwardly as at 108 to engage a tooth to retain said slide and slur cam 75

in adjusted position permitting movement of said nut rearward and retaining it in adjusted rotary position on rearward movement of said slur cam 76 and slide 62.

5 It is thus apparent that I have provided a novel type of slur cam including a slide therefor compactly mounted within a suitable housing slidable on the slur cam guide bar and actuated by the slur cam bar and in which said slide and slur 10 cam are transversely reciprocal therein and are provided with means within said housing to continuously urge said slur cam forward permitting yielding rearward motion thereof when said slur cam is set too close to the verge plate or an obstruction falls between the rear edge of the verge 15 plate and the front edges of the sinker backs and that I have provided in combination therewith means to adjust the normal transverse position of said slur cam, said means permitting yielding motion of said slur cam for any of the reasons 20 mentioned hitherto and that I have provided such a slur cam particularly adapted for use on straight knitting machines having horizontally reciprocal sinkers, of a simple and durable construction with the additional advantages explained in detail above.

It is understood that my invention is not limited to the specific embodiment shown and that various deviations may be made therefrom without departing from the spirit and scope of the appended claims.

What I claim is:

1. In a straight knitting machine, a section of horizontally reciprocatable sinkers, a cooperating number of jacks each vertically pivotally mounted on said machine to horizontally reciprocate its respective sinker, a slur cam guide bar stationarily and a slur cam bar reciprocally mounted in the rear thereof, and a slur cam for pivoting said jacks comprising a plate mounted on said slur cam guide bar and attached to said slur cam bar and having ribs projecting upwardly therefrom forming a transverse guideway and stop means projecting upwardly substantially centrally of the rear portion of said guideway and a lug projecting rearwardly therefrom slightly spaced from the center thereof, a transversely movable slide mounted in said guideway to have the side walls continuously abut the front and rear portions of said ribs and to project forwardly beyond the front edge of said plate having a central transverse slot and a screw projecting substantially centrally rearwardly thereof, a flat slur cam plate having on the front cam edge thereof a flat central portion and portions tapering rearwardly therefrom and the rear end thereof secured underneath the front projecting end of said slide, spring means abutting said stop 50 means and the front end of said slot to yield to permit rearward movement of said slur cam slide, a circular nut having teeth on the periphery thereof threadedly adjustably mounted on said rearwardly projecting screw means having the front edge thereof abutting said plate lug, and a flat spring projecting from said plate over said teeth terminating in an end slidable over said teeth on turning of said nut to engage a tooth to retain said slide and slur cam in adjusted position permitting movement of said nut rearwards in retained adjusted position on rearward movement of said slur cam and slide and plate means mounted on said ribs and extending over said slide to retain said slide within said guideway.

2. In a straight knitting machine, a section of horizontally reciprocatable sinkers, a cooperating number of jacks each vertically pivotally mounted on said machine to horizontally reciprocate its respective sinker, a slur cam guide bar 5 stationarily and a slur cam bar reciprocally mounted in rear thereof, and a slur cam for pivoting said jacks, comprising a hollow transverse guideway forming housing mounted on said slur cam guide bar and attached to said slur cam bar and having open front and rear ends and stop means projecting upwardly substantially centrally of the rear portion of said guideway, and a lug projecting rearwardly from said housing slightly spaced from the center thereof, a transversely movable slide mounted in said guideway to have the side walls continuously abut the front and rear portions of said guideway, having a central transverse slot, a screw projecting substantially centrally rearwardly thereof and a slur cam on the front edge thereof, having a flat central portion and portions tapering rearwardly therefrom, spring means abutting said stop means and the front end of said slot to yield to permit rearward movement of said slide and slur cam, a circular nut having teeth on the periphery thereof threadedly adjustably mounted on said rearwardly projecting screw means having the front edge thereof abutting said housing lug, and a flat spring projecting from said housing over said teeth terminating in an end slid- 30 able over said teeth on turning of said nut to engage a tooth to retain said slide and slur cam in adjusted position permitting movement of said nut rearwards in retained adjusted position on rearward movement of said slur cam and slide.

3. In a straight knitting machine, a section of horizontally movable sinkers, a cooperating number of jacks each vertically pivotally mounted on said machine to horizontally reciprocate its respective sinker, a slur cam guide bar stationarily and a slur cam bar reciprocally mounted in rear thereof, and a slur cam for pivoting said jacks comprising a plate adapted to be mounted on said slur cam guide bar and attached to said slur cam bar and having ribs projecting upwardly therefrom forming a transverse guideway, and a lug projecting rearwardly therefrom slightly spaced from the center thereof, a transversely movable slide mounted in said guideway to have the side walls continuously abut the front and rear portions of said ribs and to project forwardly beyond the front edge of said plate and a screw projecting substantially centrally rearwardly thereof, a flat slur cam plate having on the front cam edge thereof a flat central portion and portions tapering rearwardly therefrom and the rear end thereof secured underneath the front projecting end of said slide, spring means abutting said plate and slide to normally urge said slide 50 forwards yieldable to permit rearward movement thereof, a circular nut having teeth on the periphery thereof threadedly adjustably mounted on said rearwardly projecting screw means having the front edge thereof abutting said plate lug, and a flat spring projecting from said plate over said teeth terminating in an end slidable over said teeth on turning of said nut to engage a tooth to retain said slide and slur cam in adjusted position permitting movement of said nut rearwards in retained adjusted position on rearward movement of said slur cam and slide and plate means mounted on said ribs and extending over said slide to retain said slide within said guideway.

4. In a straight knitting machine, a section of horizontally movable sinkers, a cooperating number of jacks each vertically pivotally mounted on said machine to horizontally reciprocate its respective sinker, a slur cam guide bar stationarily and a slur cam bar reciprocally mounted in rear thereof, and a slur cam for pivoting said jacks comprising a hollow transverse guideway forming housing mounted on said slur cam guide bar and attached to said slur cam bar and having open front and rear ends and a lug projecting rearwardly therefrom slightly spaced from the center thereof, a transversely movable slide mounted in said guideway to have the side walls continuously abut the front and rear portions of said guideway to project forwardly beyond the front edge of said plate, a screw projecting substantially centrally rearwardly thereof, and a slur cam on the front edge thereof having a flat central portion and portions tapering rearwardly therefrom, spring means mounted in said housing normally urging said slide forward yieldable to permit rearward movement of said slur cam slide, a circular nut having teeth on the periphery thereof threadedly adjustably mounted on said rearwardly projecting screw means having the front edge thereof abutting said plate lug, and a flat spring projecting from said plate over said teeth terminating in an end slidable over said teeth on turning of said nut to engage a tooth to retain said slide and slur cam in adjusted position permitting movement of said nut rearwards in retained adjusted position on rearward movement of said slur cam and slide.
5. In a straight knitting machine, a section of horizontally movable sinkers, a cooperating number of jacks each vertically pivotally mounted on said machine to horizontally reciprocate its respective sinker, a slur cam guide bar stationarily and a slur cam bar reciprocally mounted in rear thereof, and a slur cam for pivoting said jacks comprising a plate mounted on said slur cam guide bar and attached to said slur cam bar and having ribs projecting upwardly therefrom forming a transverse guideway and stop means projecting upwardly substantially centrally of the rear portion of said guideway, a transversely movable slide mounted in said guideway, to have the side walls continuously abut the front and rear portions of said ribs and to project forwardly beyond the front edge of said plate having a central transverse slot, a flat slur cam plate having on the front cam edge thereof a flat central portion and portions tapering rearwardly therefrom and the rear end thereof secured underneath the front projecting end of said slide, spring means abutting said stop means and the front end of said slot to yield to permit rearward movement of said slur cam slide, and means to adjust the normal transverse position of said slide permitting rearward movement thereof on rearward movement of said slur cam plate, and plate means mounted on said ribs and extending over said slide to retain said slide within said guideway.
6. In a straight knitting machine, a section of horizontally reciprocatable sinkers, a cooperating number of jacks each vertically pivotally mounted on said machine to horizontally reciprocate its respective sinker, a slur cam guide bar stationarily and a slur cam bar reciprocally mounted in rear thereof, and a slur cam for pivoting said jacks, comprising a hollow transverse guideway forming housing mounted on said slur cam guide bar and attached to said slur cam bar and having open front and rear ends and stop means projecting upwardly substantially centrally of the rear portion of said guideway, a transversely movable slide mounted in said guideway, to have the side walls continuously abut the front and rear portions of said guideway having a central transverse slot, a slur cam on the front cam edge thereof, having a flat central portion and portions tapering rearwardly therefrom, spring means abutting said stop means and the front end of said slot normally urging said slide forwardly yieldable to permit rearward movement thereof and means to adjust the normal transverse position of said slide permitting rearward movement thereof.
7. In a straight knitting machine, a section of horizontally reciprocatable sinkers, a cooperating number of jacks each vertically pivotally mounted on said machine to horizontally reciprocate its respective sinker, a slur cam guide bar stationarily and a slur cam bar reciprocally mounted in the rear thereof, and a slur cam for pivoting said jacks comprising a hollow transverse guideway forming housing mounted on said slur cam guide bar and attached to said slur cam bar and having open front and rear ends and stop means projecting upwardly substantially centrally of the rear portion of said guideway, a transversely movable slide mounted in said guideway, to have the side walls continuously abut the front and rear portions of said guideway having a central transverse slot, a slur cam on the front cam edge thereof, having a flat central portion and portions tapering rearwardly therefrom, spring means abutting said stop means and the front end of said slot normally urging said slide forwardly yieldable to permit rearward movement thereof.
8. A slur cam comprising a plate adapted to be mounted on a slur cam guide shaft having ribs projecting upwardly therefrom forming a transverse guideway and stop means projecting upwardly substantially centrally of the rear portion of said guideway, and a lug projecting rearwardly therefrom slightly spaced from the center thereof, a transversely movable slide mounted in said guideway to have the side walls continuously abut the front and rear portions of said ribs and to project forwardly beyond the front edge of said plate having a central transverse slot and a screw projecting substantially centrally rearwardly thereof, a flat slur cam plate having on the front cam edge thereof a flat central portion and portions tapering rearwardly therefrom and the rear end thereof secured underneath the front projecting end of said slide, spring means abutting said stop means and the front end of said slot to yield to permit rearward movement of said slur cam slide, a circular nut having teeth on the periphery thereof threadedly adjustably mounted on said rearwardly projecting screw means having the front edge thereof abutting said plate lug, and a flat spring projecting from said plate over said teeth terminating in an end slidable over said teeth on turning of said nut to engage a tooth to retain said slide and slur cam in adjusted position permitting movement of said nut rearwards in retained adjusted position on rearward movement of said slur cam and slide and plate means mounted on said ribs and extending over said slide to retain said slide within said guideway.
9. A slur cam comprising a hollow transverse guideway forming housing adapted to be mounted on a slur cam guide shaft having open front and rear ends and stop means projecting upwardly substantially centrally of the rear portion of said guideway, a transversely movable slide mounted in said guideway, to have the side walls continuously abut the front and rear portions of said guideway having a central transverse slot, a slur cam on the front cam edge thereof, having a flat central portion and portions tapering rearwardly therefrom, spring means abutting said stop means and the front end of said slot normally urging said slide forwardly yieldable to permit rearward movement thereof and means to adjust the normal transverse position of said slide permitting rearward movement thereof.

rear ends and stop means projecting upwardly substantially centrally of the rear portion of said guideway, and a lug projecting rearwardly from said housing slightly spaced from the center thereof, a transversely movable slide mounted in said guideway to have the side walls continuously abut the front and rear portions of said guideway having a central transverse slot, a screw projecting substantially centrally rearwardly thereof, and a slur cam on the front edge thereof having a flat central portion and portions tapering rearwardly therefrom, spring means abutting said stop means and the front end of said slot to yield to permit rearward movement of said slide and slur cam, a circular nut having teeth on the periphery thereof threadedly adjustably mounted on said rearwardly projecting screw means having the front edge thereof abutting said housing lug, and a flat spring projecting from said housing over said teeth terminating in an end slidable over said teeth on turning of said nut to engage a tooth to retain said slide and slur cam in adjusted position permitting movement of said nut rearwards in retained adjusted position on rearward movement of said slur cam and slide.

10. A slur cam comprising a hollow transverse guideway forming housing adapted to be mounted on a slur cam guide shaft having open front and rear ends and stop means projecting upwardly substantially centrally of the rear portion of said guideway, and a lug projecting rearwardly therefrom slightly spaced from the center thereof, a transversely movable slide mounted in said guideway to have the side walls continuously abut the front and rear portions of said guideway and to project forwardly beyond the front edge of said plate having a central transverse slot, a screw projecting substantially centrally rearwardly thereof, and a slur cam on the front edge thereof having a flat central portion and portions tapering rearwardly therefrom, spring means abutting said stop means and the front end of said slot normally urging said slide forwards yieldable to permit rearward movement of said slur cam slide, a circular nut having teeth on the periphery thereof threadedly adjustably mounted on said rearwardly projecting screw means having the front edge thereof abutting said plate lug, and a flat spring projecting from said plate over said teeth terminating in an end slidable over said teeth on turning of said nut to engage a tooth to retain said slide and slur cam in adjusted position permitting movement of said nut rearwards in retained adjusted position on rearward movement of said slur cam and shaft.

11. A slur cam comprising a plate adapted to be mounted on a slur cam guide shaft having ribs projecting upwardly therefrom forming a transverse guideway and stop means projecting upwardly substantially centrally of the rear portion of said guideway, a transversely movable slide mounted in said guideway, to have the side walls continuously abut the front and rear portions of said ribs and to project forwardly beyond the front edge of said plate having a central transverse slot, a flat slur cam plate having on the front cam edge thereof a flat central portion and portions tapering rearwardly therefrom and the rear end thereof secured underneath the front projecting end of said slide, spring means abutting said stop means and the front end of said slot to yield to permit rearward movement of said slur cam slide, and means to adjust the normal transverse position of said plate permitting rearward movement thereof on rearward movement of said slur cam plate and plate means mounted on said ribs and extending over said slide to retain said slide within said guideway.

12. A slur cam comprising a hollow transverse guideway forming housing adapted to be mounted on a slur cam guide shaft having open front and rear ends and stop means projecting upwardly substantially centrally of the rear portion of said guideway, a transversely movable slide mounted in said guideway, to have the side walls continuously abut the front and rear portions of said guideway having a central transverse slot and a slur cam on the front cam edge thereof, having a flat central portion and portions tapering rearwardly therefrom, spring means abutting said stop means and the front end of said slot normally urging said slide forwards yieldable to permit rearward movement thereof and means to adjust the normal transverse position of said slide permitting rearward movement thereof.

13. A slur cam comprising a hollow transverse guideway forming housing adapted to be mounted on a slur cam guide shaft having open front and rear ends and stop means projecting upwardly substantially centrally of the rear portion of said guideway, a transversely movable slide mounted in said guideway to have the side walls continuously abut the front and rear portions of said guideway having a central transverse slot and a slur cam on the front cam edge thereof having a flat central portion and portions tapering rearwardly therefrom and spring means abutting said stop means and the front end of said slot normally urging said slide forwards yieldable to permit rearward movement thereof.

GEORGE F. KETTLEBAND.
